ABSTRACT OF THE DISCLOSURE

A mounting structure for securing an antenna to the exterior surface of a mobile home or the like. The structure includes an elongated tubular post having a plurality of laterally facing vacuum cups secured thereto for gripping the exterior surface of the mobile home. An adhesive is positioned between the cups and the exterior surface to increase the bond therebetween.

The present invention relates to a mounting structure for an antenna which is particularly useful in attaching an antenna to a mobile home or the like which has a relatively smooth exterior surface.

It is conventional practice to attach a television antenna mast to the outside skin of a mobile home body by drilling a hole in the skin and thereafter riveting, bolting, or otherwise securing the mast thereto. The resulting holes not only present an unsightly appearance when the mast is removed, but they also permit entry of water, wind, and foreign materials to the inside wall areas of the home. In addition, since the skin is generally of a light gauge sheet metal, the rivets or bolts are often easily pulled out of the holes by the wind forces acting on the antenna.

It is accordingly an object of the present invention to provide an antenna mounting structure for a mobile home which may be firmly secured to the exterior surface without puncturing the skin surface.

It is a further object of this invention to provide an antenna mounting structure which does not mar or otherwise disfigure the skin surface, and which may be easily and quickly attached thereto.

It is another object of the present invention to provide a structure which is adapted to securely mount an antenna to a mobile home and which is capable of withstanding wind forces over an extended period of time.

These and other objects and advantages of the present invention are achieved in the embodiment illustrated herein by the provision of an antenna mounting structure which comprises an elongated tubular post and a plurality of laterally facing longitudinally spaced vacuum cups secured thereto. An adhesive is positioned between the cups and the exterior skin of the mobile home to increase the bond therebetween.

Some of the objects of the invention having been stated, other objects will appear as the description proceeds, when taken in connection with the accompanying drawings, in which—

FIG. 1 is a perspective view of a mobile home having an antenna mounting structure incorporating the features of the present invention secured thereto;

FIG. 2 is a side elevational view of the mounting structure; and

2

FIG. 3 is an enlarged perspective view illustrating the upper portion of the mounting structure.

Referring to the drawings, a typical mobile home is illustrated and is designated by the numeral 10. The mobile home is provided with the usual trailer towing hitch 12, and it includes four side walls 14, 15, 16 and 17, each having a relatively smooth exterior sheet metal outer skin. While all four side walls are relatively smooth in the illustrated embodiment, it will be appreciated that with the present invention, only a portion of the outer skin surface need be smooth, and that the remainder could for example be corrugated.

The mounting structure itself comprises an elongated tubular post 20 having a plurality of laterally facing, longitudinally spaced and aligned vacuum cups 22, 23, 24, and 25 secured thereto. The vacuum cups are of conventional construction and include a flexible circumferential forward flange (e.g. 25a) and a solid rear neck (e.g. 25b), and may be fabricated from rubber or similar resilient material. The cups are adapted to grip the smooth exterior surface of the mobile home when pressed thereagainst to firmly secure the tubular post thereto by suction.

As best seen in FIG. 3, each vacuum cup is attached to the post by means of a threaded member 26 which extends through suitable apertures (not shown) in the post. The threaded member enters the rear neck portion of each cup and is threadedly engaged thereby. In the embodiment illustrated, cups 22 and 23 are mounted in spaced relation adjacent the lower end of the post and cups 24 and 25 are mounted in spaced relation adjacent the upper end of the post such that the cups are spaced substantially along the entire length of the post.

The post 20 preferably is of sufficient length to extend well above the roof level of the mobile home. An antenna 30 is secured by a suitable flange 32 or other conventional means to the upper end of the post.

To supplement the suctional engagement between the vacuum cups and surface skin of the mobile home, a suitable adhesive, such as an epoxy resin, may be positioned on the front flange of the cups prior to engagement with the skin. Thus after the cups are pressed against the surface skin, the adhesive acts to substantially permanently secure the cups thereto.

In the drawings and specification there has been set forth a preferred embodiment of the invention, and although specific terms are employed, they are used in a generic and descriptive sense only and not for purposes of limitation.

What is claimed is:

1. In combination with a mobile home or the like having a relatively smooth exterior side wall surface and an upper roof, a mounting structure securing an antenna to said side wall surface without puncturing the same and comprising

an elongate tubular post extending vertically adjacent a substantial portion of the height of said side wall surface of said mobile home and upwardly above the roof thereof,
a plurality of laterally facing vacuum cups longitudinally spaced along substantially the entire portion of the post extending adjacent said mobile home side wall surface and secured by suction to said side wall surface to thereby retain said tubular post thereon, fastener means penetrating said post for fixedly securing each of said vacuum cups thereto, an adhesive positioned between each of said vacuum

3

cups and said side wall surface for substantially permanently securing said vacuum cups and post there-
to, and
an antenna carried at the upper end of said post.
